UNITED STATES PATENT OFFICE

164,391

LIGHTER

Willard F. Wagner, Detroit, Mich., assignor of
one-half to Charles W. Glenn, Detroit, Mich.

Application June 3, 1950, Serial No. 10,327

Term of patent 14 years

(Cl. D48—27)

To all whom it may concern:

Be it known that I, Willard F. Wagner, a citizen of the United States, residing at Detroit, in the county of Wayne and State of Michigan, have invented a new, original, and ornamental Design for a Lighter, of which the following is a specification, reference being had to the accompanying drawing forming part thereof.

Fig. 1 is a perspective view of a lighter showing my new design, the lighter being in closed position, and

Fig. 2 is a perspective view thereof showing the lighter open and the inner casing in depressed position.

The side of the lighter opposite to that illus-

trated in the figures is the same as that shown in the drawing.

I claim:

The ornamental design for a lighter, as shown and described.

WILLARD F. WAGNER.
